UNITED STATES PATENT OFFICE.

RAYMOND RUSK, DECEASED, LATE OF SAN ANGELO, TEXAS, BY CLARA RUSK, ADMINISTRATRIX, OF SAN ANGELO, TEXAS, ASSIGNOR OF ONE-HALF TO JAMES W. LINDSEY, OF SAN ANGELO, TEXAS.

LIFEBOAT.

1,322,957.

Specification of Letters Patent. Patented Nov. 25, 1919.

Application filed June 18, 1919. Serial No. 305,138.

To all whom it may concern:

Be it known that RAYMOND RUSK, deceased, late a citizen of the United States, and resident of San Angelo, in the county 5 of Tom Green and State of Texas, United States of America, invented new and useful Improvements in Lifeboats; and that I, CLARA RUSK, being duly constituted administratrix of the estate of RAYMOND RUSK, 10 do hereby declare the following to be a full, clear, and exact description of said invention, such as will enable others skilled in the art to which it appertains to make and use the same.

15 This invention relates to new and useful improvements in boats, and more particularly to life boats.

The principal object of the invention is to provide improved means for preventing the 20 boat from capsizing.

Another object of the invention is to provide a skeleton supporting structure or frame in which a boat is so mounted that the frame may rotate around it while the 25 boat floats on the water, said frame being equipped with means for preventing its sinking.

Another object is to so construct a frame of this character that the boat may be filled 30 with passengers and rolled off the side of a ship without the position of the boat being changed and which renders it especially desirable for use in connection with life boats.

With the foregoing and other objects in 35 view, which will appear as the description proceeds, the invention resides in the combination and arrangement of parts and in the details of construction hereinafter described and claimed, it being understood that 40 changes in the precise embodiment of the invention herein disclosed may be made within the scope of what is claimed without departing from the spirit of the invention.

In the accompanying drawings:—

45 Figure 1 represents a perspective view of a boat and its supporting structure constructed in accordance with this invention, one end of the structure being broken off for convenience in illustration,

50 Fig. 2 is a detail longitudinal section through a portion of one of the air tanks showing the connector which unites it at one end to the boat, and

55 Fig. 3 is a detail sectional view taken on the line 3—3 of Fig. 1.

In the embodiment illustrated, a skeleton body or frame 1 is shown of substantially cigar or torpedo shape, in which a boat B is mounted. This frame is constructed of curved longitudinally disposed laterally 60 spaced beams 2 composed of any suitable material and converging toward their ends. These ends are secured to the centers 4 of double cone-shaped air tanks 3, being secured thereto by any suitable means, it being 65 understood that one tank is mounted at each end of the frame, the outer cones forming the noses of the frame.

Secured to the beams 2 midway their ends is a ring 5 of channel iron having inturned 70 flanges 6 along its side edges to form a housing and guide for a sliding member 7 placed within said ring and to which is secured a plurality of arms 8 which project radially inward between flanges 6 and are secured to 75 the boat B.

The ends of the boat B are swiveled to the inner apices of the air tanks 3 by means of Y-shaped connectors 10, the shanks 11 of which are round and rotate in bearings 12 80 carried by the apices of the tanks. The free ends of shanks 11 have flat heads 13 which operate to hold the shanks against withdrawal from the tanks, while partitions 3^a in the tank ends serve as stops to 85 limit their inward movement. The flared arms 14 of the members 10 are made flat and are designed to receive between them the pointed ends of boat B and to be bolted thereto.

90 It will thus be seen that the frame 1 may rotate around the boat and prevent the boat from capsizing.

If found necessary a plurality of rings such as those shown at 5 may be used to 95 strengthen the structure, rollers 9 being preferably arranged between member 6 and housing 5 to facilitate the turning of member 5.

By constructing the air tanks in torpedo 100 or cigar shape, the passage of the frame or body through the water will be facilitated.

One or more of the ribs or beams 2 may be made in sections hinged as shown at 15 and connected by a catch 16 to provide for 105 the rapid entrance of passengers to the boat.

From the above description it will be obvious that a boat B mounted as described in the frame 1 will be held at all times in position so that the passengers will remain 110

upright and tilting and rocking of the boat will be prevented, the frame 1 turning transversely around the boat and the air tanks 3, insuring the floating of the frame at all 5 times.

From the foregoing description, taken in connection with the accompanying drawings, the advantages of the construction and of the method of operation will be readily 10 apparent to those skilled in the art to which the invention appertains and while I have described the principle of operation of the invention together with the device which I now consider to be the best embodiment 15 thereof, I desire to have it understood that the device shown is merely illustrative and that such changes may be made as are within the scope of the claimed invention.

Having thus fully described my invention, what I claim as new and desire to secure by Letters Patent, is:—

1. A buoyant supporting frame for boats comprising a substantially cigar-shaped skeleton body, an air tank mounted at each 25 end of said body, an annular member mounted at the center of said frame and encircling the boat to be supported thereby, a movable connection between said boat and said annular member, the ends of the boat 30 having swiveled connection with the tanks.

2. A buoyant supporting frame for boats comprising a substantially cigar-shaped skeleton body, a double cone-shaped air

tank mounted at each end of said body, an annular member mounted at the center of 35 said frame and encircling the boat to be supported thereby, arms extending from said boat and fixed thereto, and a movable member connected to said arms and guided by said annular member, the ends of the 40 boat having swiveled connection with the inner apices of the tanks.

3. A buoyant boat supporting frame comprising a skeleton cigar-shaped body having double cone-shaped tanks located one at each 45 end of said body, Y-shaped connectors rotatably mounted in the inner apices of said tanks and held against withdrawal therefrom, the arms of said connectors being designed to straddle the ends of a boat and be fixedly connected thereto, and an annular member fixed to the center of said frame and encircling the boat transversely when applied, a member slidably in said annular member and fixedly connected to the boat 50 when in use.

In testimony whereof, I, CLARA RUSK, administratrix of the estate of RAYMOND RUSK, have hereunto set my hand in the presence of two subscribing witnesses.

MRS. CLARA RUSK,
Administratrix of Raymond Rusk, deceased.
